[57] **CLAIM**

The ornamental design for an overload-protected electrical receptacle-multiplying plug or similar article, as shown and described.

DESCRIPTION

FIG. 1 is a frontal perspective view of an overload-protected electrical receptacle-multiplying plug or similar article showing my new design;

FIG. 2 is a left side elevational view thereof, the right side being substantially identical;

FIG. 3 is a rear perspective view thereof; and

FIG. 4 is a top plan view thereof.

The right side is a mirror image of the left side thereof.
